Friedrich Wm Becker

UNITED STATES PATENT OFFICE.

FRIEDERICH WM. BECKER, OF NEW ATHENS, ILLINOIS.

FAN ATTACHMENT FOR ROCKING-CHAIRS AND CRADLES.

984,462.

Specification of Letters Patent. Patented Feb. 14, 1911.

Application filed August 2, 1909. Serial No. 510,896.

To all whom it may concern:

Be it known that I, FRIEDERICH W. BECKER, a citizen of the United States, residing at New Athens, in the county of St. Clair and State of Illinois, have invented new and useful Improvements in Fan Attachments for Rocking-Chairs and the Like, of which the following is a specification.

This invention relates to improvements in fan attachments for rocking chairs, cradles, and the like.

One object of the invention is the provision of a device actuated by the rocking movement of the chair or cradle to which it is applied to direct a current of air onto the head of the occupant of the chair or cradle.

Another object is the provision of a device which may be readily applied to most forms of rocking chairs or cradles now in use without necessitating any expensive alterations in the structure of the chair or cradle.

With the above and other objects in view, which will more fully hereinafter appear, the present invention consists in certain novel details of construction and arrangement of parts, hereinafter fully described, illustrated in the accompanying drawings, and more particularly pointed out in the appended claims; it being understood that various changes in the form, proportion, size, and minor details of the device may be made, within the scope of the appended claims, without departing from the spirit or sacrificing any of the advantages of the invention.

In the accompanying drawings, forming part of the specification;—Figure 1 is a side elevation of the device showing its application to a rocking chair. Fig. 2 is a sectional end view on the line 2—2 of Fig. 1. Fig. 3 is a detail side elevation with the upper end portion of the fan shaft and spring removed. Fig. 4 is a detail side elevation of the guide for the fan shaft. Fig. 5 is a plan view of the same.

Similar numerals of reference are employed to designate corresponding parts throughout.

The legs of the rocking chair are designated by the numerals 5 and 6, the rockers one of which is shown connecting two of the said legs is designated by the numeral 7, and the seat supported by said legs being designated by the numeral 8. Since these parts are all of well-known construction a

detail description of the same need not be given.

The device forming part of the subject matter of the present invention is shown to include a bracket of substantially right angular contour, the opposite sides of which are designated by the numerals 9 and 10. These sides are unequal in length the longer side 9 being slightly curved to conform to the curvature of the rocker 7. The bracket is arranged on the inner surface of the rocker 7 and at a point substantially intermediate the front end and the middle of the rocker, the side 9 extending parallel with the rocker and having openings 11 for the reception of screws or the like which are screwed into the inner surface of the rocker 7. When the bracket is positioned on the rocker in the manner just described the side 10 will extend upwardly from the upper side of the rocker, and formed on the outer surface of the side 10 is a lug 12, which extends over the upper side of the rocker 7, its outer end lying slightly beyond the outer face of the said rocker 7. Formed on the upper side of the lug 12 and adjacent to the free end thereof is a medially disposed socket 13.

By reference now to Fig. 1 it will be seen that extending beyond one side of the seat 8 and in alignment with the bracket is a rod 14. The outer end of this rod is provided with an opening 15 to align with the socket 13. The rod is adjustably secured to the seat in the following manner:—

By reference now to Fig. 4 it will be seen that an oblong plate 16 is provided with a plurality of openings 17 for the reception of screws by means of which the plate is secured to the lower face of the seat 8. Depending from the plate are a pair of spaced bosses 18 having alining transverse openings for the reception of the inner end portion of the rod 14. Threaded into the lower ends of the posts 18 are set screws 19, the inner ends of which when binding on the rod 14 prevent endwise movement thereof. Passing through the opening 15 at the outer end of the rod 14 is a fan shaft 20. The lower end portion of this shaft is reduced as shown at 21 and is loosely received by the socket 13. The shaft 20 is hollow and receives a shaft 22, the said shaft 22 being adjustably secured within the shaft 20 by means of a set screw 23 passing through the upper end

portion of the shaft 20. With this construction it will be seen that the fan shaft is extensible, and may be adjusted to various distances from the seat 8. The outer or upper 5 end of the shaft 22 is provided with a transverse opening which receives the shanks 24 and 25 of a pair of fan blades 26 and 27, the said shanks extending in opposite directions and being secured against displacement 10 by means of set screws 28, extending through the upper end portion of the shaft 22.

By reference now to the drawings it will be seen that keyed or otherwise secured to the lower end portion of the shaft 20 is a 15 beveled pinion 29 and pivoted adjacent to the upper end portion of the side 10 of the bracket is a toothed segment 30, the teeth of which mesh with the pinion 29. The segment 30 is provided with a radial shank 31, 20 the function of which will presently appear.

An oscillating arm is designated by the numeral 32, the said arm being somewhat greater in length than the length of the longer side 9 of the bracket and having its 25 medial portion pivoted to the bracket, as shown at 33, said arm being arranged over the inner face of the bracket its pivotal point being at the point of juncture of the sides 9 and 10, or approximately so. Secured to one end of the oscillating arm is an angular-shaped hanger 33, the said hanger extending downwardly from the arm and thence toward the opposite end thereof and supporting a roller 34. The opposite end 30 of the oscillating arm 32 is provided with an eye 35, and connecting the said eye with the seat 8 of the chair is a helical retractile spring 36, the function of which is to yieldingly hold the roller 34 in engagement with 40 the floor or other supporting surface for the rocker.

Extending upwardly from the arm 32 and at a point adjacent the hanger 33 is an upright 37, the said upright being considerably 45 less in length than the length of the arm 32 and connection between the upper end of the upright 37 and the radial arm 31 of the toothed segment 30 is established by means of a pitman 38, the opposite ends of which 50 are pivoted to the upright and arm 31.

With this construction it will be manifest when the chair is rocked the arm 32 will be oscillated relatively to the rocker 7, whereupon the pitman and toothed segment will 55 be likewise oscillated and turning movement imparted to the sections of the fan shaft. It will be seen that during each complete oscillation of the rocker 7 turning movement

in opposite directions will be imparted to the fan blades 26 and 27 so that a current 60 of air will be directed onto the occupant of the chair or cradle to which the device is applied.

From the foregoing, it is evident that I have provided a device which is comparatively simple in structure and inexpensive in manufacture, embodying few parts and these so arranged that the danger of derangement will be reduced to a minimum.

I claim:

1. A fan attachment for rocking chairs and the like comprising a bracket adapted to be secured to the rocker, a lateral socketed extension arranged on one face of the bracket, an oscillating arm arranged on one 75 face of the bracket, a roller arranged on one end of the arm, a spring member serving to hold the roller in engagement with the ground and connected at one end to the opposite end of the oscillating arm and adapted to be connected at its opposite end to the 80 rocking chair, a rotatable fan shaft connected to the rocking chair and having at one end thereof a plurality of fan blades, and having its opposite end arranged in the 85 socket of the extension, and a connection between the fan shaft and oscillating arm, for the purpose described.

2. A fan attachment for rocking chairs and the like comprising a bracket adapted to 90 be secured to the rocker, a lateral socketed extension arranged on one face of the bracket, an oscillating arm arranged on the opposite face of the bracket, a roller arranged on one end of the arm, a spring 95 member serving to hold the roller in engagement with the ground and connected at one end to the opposite end of the oscillating arm and having its opposite end adapted to be secured to the rocking chair, a rotatable 100 fan shaft connected to the chair and having at its upper end a plurality of fan blades, and having its lower end arranged in the socket of the said extension, a pinion arranged at the lower end portion of the fan 105 shaft, an oscillating gear member carried by the bracket and meshing with the pinion, and pitmen connecting the gear member with the oscillating arm.

In testimony whereof I affix my signature 110 in presence of two witnesses.

FRIEDERICH WM. BECKER.
